The ornamental design for an alcoholic beverage bottle, as shown and described.

DESCRIPTION

FIG. 1 is a perspective view of an alcoholic beverage bottle showing the new design;

FIG. 2 is a front view thereof;

FIG. 3 is a rear view thereof;

FIG. 4 is a right-side view thereof;

FIG. 5 is a left-side view thereof;

FIG. 6 is a top view thereof; and,

FIG. 7 is a bottom view thereof.

The broken lines show portions of an alcoholic beverage bottle that form no part of the claimed design.
